UNITED STATES PATENT OFFICE.

ROBERT C. BLACKALL, OF ALBANY, NEW YORK.

RELIEF-VALVE FOR LOCOMOTIVE-ENGINES.

SPECIFICATION forming part of Letters Patent No. 283,749, dated August 28, 1883.

Application filed July 5, 1882. (No model.)

To all whom it may concern:

Be it known that I, ROBERT C. BLACKALL, of the city and county of Albany, and State of New York, have invented certain new and 5 useful Improvements in Relief-Valves for Locomotive-Engines, of which the following is a full and exact description, reference being had to the accompanying drawings, making part of this specification, and in which—

10 Figure 1 is an elevation of the front end of a locomotive boiler and cylinders, showing one side in section for the purpose of exhibiting underlying parts that are affected by my invention; Fig. 2, a side elevation of the same, 15 with parts in section for the purpose above described; and Fig. 3, a vertical section of one form of relief-valve I use for effectuating my invention.

The object of my invention is to remedy a 20 defect now existing in locomotive-engines, and which is made manifest when, in attempting to avert an accident, the valve motion of the engine is suddenly reversed while the engine is moving ahead at a rapid rate of speed.

25 Whenever such a reversal is effected the cylinders of the engine operate as "air-compressors" to fill either the boiler or steam pipes—according to the condition of the communicating parts that are open to the said cylinders—with a large volume of air under great 30 pressure; and if such reversal occurs after the throttle-valve has been closed, it is always attended by the blowing-off of the steam-chests, and thereby the engine is left in an unman-

35 ageable condition, and, for the time, is a useless wreck in the presence of a danger that the engineer has been striving to avoid. On the other hand, if the said reversal is effected while the throttle-valve remains open, the air 40 forced into the boiler by the action of the pistons of the steam-cylinders soon produces an excessive accumulation of pressure in the boiler that will strain it to such a degree that it soon becomes absolutely dangerous.

45 To remedy this defect my invention consists in providing the engine with an automatic relief-valve placed at any point between the throttle-valve and slide-valves, preferably upon the steam-chest, where it will have a free and open 50 communication with the steam-pipes of the engine only. Said relief-valve, adjusted to open at a slightly higher pressure than the

maximum pressure carried on the boiler, but below the degree of pressure required to produce a rupture of the parts, will permit the 55 excess of air-pressure to escape from the steam-pipes, and thereby relieve the structure from the undue strain engendered by the compression of air by the pistons, and, by means of the said relief-valve, a uniform pressure of 60 air, whose maximum point will be within the limit of safety, will be maintained in the steam-pipes and steam-chests (while the engine is in motion, the steam shut off, and the valve motion reversed) to serve as an opposing medium 65 to resist the movement of the pistons of the engine, which resistance will quickly overcome the momentum of the moving train and stop its motion; and in this respect the volume of air maintained in a state of compression in the steam-pipes and steam-chests will, 70 in conjunction with the pistons of the engine, perform the functions of an atmospheric brake in stopping the motion of the train.

As illustrated in the drawings, A represents 75 the forward end of the boiler of a locomotive-engine; B, the cylinders of the engine; C, the steam-chests for containing the slide-valves of the engine; C, the steam-chest covers; D, the throttle-valve; E, the main steam-pipe; E', 80 the branch steam-pipes for connecting the pipe E with the cylinders B, and F the steam-passages for conveying steam into the steam-chests. All of the aforementioned parts, being the usual and well-known constituent parts 85 of an ordinary locomotive-engine, do not of themselves constitute my invention.

It will be seen, and must be clearly understood, that a free and uninterrupted communication is always open between the steam-chests C, steam-pipes E and E', and steam-passages F; and, it must also be understood, whenever the pistons are reciprocating in the cylinders B, there is, by the operation of the slide-valves of the engine, an intermittent communication established between the interior of said cylinders and the steam-chests and steam-pipes.

G is a relief-valve, which I employ for effectuating my invention, and which may be of 100 any suitable style of spring-actuating puppet-valve. Said valve may be applied at any accessible part of the engine where a direct communication may be obtained for said valve

either with the steam-chests or steam-pipes. As indicated by the arrow marked 1, the relief-valve G is placed over the top of the boiler, and communicates with the main steam-pipe 5 E where the said pipe extends into the smoke-arch of the boiler. As indicated by arrow 2, said relief-valve communicates with the steam-passage F, and, as indicated by arrow 3, it is inserted in the cover e of one of the steam-chests.

Storage-tanks may be connected with the escape-pipes of the relief-valves for receiving the compressed air discharged from said valves, which air may then be utilized when required 15 for operating air-brakes in the usual manner.

It will be readily understood by those versed in steam-engineering that while a locomotive with a train of cars is running in either direction at any considerable rate of speed, if the 20 valve motion of the engine is suddenly reversed it will not immediately effect the stoppage of the train, but, on the contrary, the momentum of the train will compel it to continue its course for a time and cause the slide-valves 25 to move in a direction that is contrary to that required by the movement of the pistons, and, as a result of this action, the pistons will continue to draw air into the cylinders through the exhaust-openings and expel it (the air) 30 from the cylinders through the steam-ports into the steam-chests and steam-pipes, wherein—in the absence of any suitable means of escape—it will become so excessively com-

pressed that the steam-chests will be blown off, and the locomotive will become an unmanageable wreck. By means of relief-valves G, as herein shown and described, the accumulated pressure in the steam-chests and steam-pipes is, at its maximum, kept below the point where it can produce a rupturing strain, and— 40 as an incident due to my invention—the compressed air confined in the steam chests and pipes will resist the movements of the pistons and quickly stop the motion of the train.

I am aware that relief-valves have heretofore been used in the cylinder-heads and at intermediate points between the slide-valves and pistons of steam-engines for the purpose of preventing the blowing off of the cylinder-heads; but while such arrangements require 50 twice the number of relief-valves, (one at each end of the cylinder,) they do not effect the purpose for which my invention is designed. Therefore I do not broadly claim the use of relief-valves on engine-cylinders; but 55

I claim as my invention—

In a locomotive-engine, the combination, with the steam-chest of an engine-cylinder, of an automatic relief-valve located intermediate between the slide-valve and throttle-valve, and arranged to operate as and for the purpose herein specified.

ROBERT C. BLACKALL.
